UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

MEANS FOR ADJUSTING STEREOTYPE PLATES ON PLATE CYLINDERS.

Application filed August 21, 1920. Serial No. 405,046.

To all whom it may concern:

Be it known that I, HENRY F. BECHMAN, a citizen of the United States, residing at Battle Creek, in the county of Calhoun and State of Michigan, have invented certain new and useful Improvements in Means for Adjusting Stereotype Plates on Plate Cylinders; and I hereby declare that the following is a full, clear, and exact description thereof, reference being had to the accompanying drawings, which form part of this specification.

This invention is an improvement in stereotype plate printing presses and has particular reference to the plate cylinder and means for attaching plates to such cylinder.

The object of the invention is to enable a plate cylinder to properly carry plates slightly varying in length and to provide means to compensate for variations in the actual length of a stereotype plate due to whether or not the plates are cast from dry matrices or wet matrices.

It has been found that an ordinary newspaper-page stereotype-plate, if cast from a dry matrix, will shrink about one-fourth of an inch more than if cast from a wet matrix. Ordinarily the plate cylinders are made for certain size of stereotype plate, and if the stereotypers change from using wet matrices to using dry matrices, or vice versa, the plates do not properly fit and the cylinders have to be rectified. Furthermore, ordinary plate cylinders are made for a certain size of stereotype-page-plate, such as seven columns 13-ems, or eight columns 13-ems, etc.; and if the publisher wants to change the size of his pages it is very expensive and troublesome to do so, sometimes requiring remaking of the plate cylinders.

The present invention provides means whereby the plate cylinders can be readily adapted to accommodate various sizes of plates cast either from wet or dry matrices. For this purpose the plate cylinder is provided with an adjustable but normally fixed plate stop or collar which, instead of being cast on or permanently secured to the cylinder, is adjustably mounted thereon as hereinafter described, and can be readily adjusted according to the size of plate to be

used and according to whether such plate is cast from a wet or a dry matrix. 55

In particular, the invention is designed for use on single page tubular plate presses of the type illustrated in my patent Reissue No. 13,129 of July 12, 1910; but of course the invention is not restricted to any particular size, form or style of press. 60

I will explain the invention with reference to the accompanying drawings, which illustrate one practical embodiment thereof, and when understood will enable others 65 skilled in the art to readily adapt and use the invention.

In said drawings:

Fig. 1 is a plan view of one end of a plate cylinder equipped with the invention. 70

Fig. 2 is a part longitudinal section and part side elevation of Fig. 1.

Fig. 3 and Fig. 3^a are respectively an enlarged end view and an edge view of part of the reversible ring. 75

Fig. 4 is a detail partly sectional view indicating how the collar may be adjusted for a 7-column 13-ems plate cast from a dry matrix.

Fig. 5 is a similar view showing the collar adjusted for a 7-column 13-ems plate cast from a wet matrix. 80

Figs. 6 and 7 are similar views showing how the column may be adjusted respectively for an 8-column 13-ems plate cast from a dry matrix (Fig. 6), or from a wet matrix (Fig. 7). 85

The cylinder 1 may be of any desired kind or construction, such as is ordinarily employed in rotary web-printing presses, 90 adapted to carry stereotype plates. It is preferably shown as a single-page tubular plate adapted to carry single page tubular plates such as shown in my aforesaid patent. This cylinder is provided with the usual groove 1^a for engagement of the inner adjustable plate clamps (not shown) 95 adapted to engage the inner end of the plate *p*, the other end of the plate abutting against a collar 3 ordinarily formed with or fastened to the cylinder. 100

In the present invention I make such collar adjustable and secure it in the desired position as hereinafter described.

As shown, the cylinder is provided near 105 its outer end, whereon the collar 3 is ap-

plied, with a plurality of circumferential grooves 1^b, which are intersected by a longitudinal slot 1^c which may merge into the outer end of the slot 1^a and form a continuation thereof, as indicated in the drawings.

The grooves 1^b are adapted to receive a stop ring 2, which is preferably made in two opposite halves so that it can be easily 10 placed around the cylinder and inserted in the groove. The ring 2 is of slightly greater exterior diameter than the external diameter of the cylinder 1, and projects out of the groove, and it is provided with a laterally projecting flange 2^a on one side, which fits closely against the surface of the cylinder adjacent the groove 1^b. The flange 2^a and portion of the ring 2 projecting out of the groove 1^b are adapted to be entered 20 into an annular recess 3^a in the outer end of the collar 3 (see Fig. 2), so that when the collar is properly positioned in place on the cylinder, the ring 2 is concealed within the recess 3^a of the collar 3, and the sections 25 of ring 2 are held in position against radial movement or displacement in the groove by the collar 3.

The ring and collar may be fastened in position on the cylinder by means of a key 4^a inserted in the slot 1^c and extending through the ring and partially through the collar as shown. One end of the key is provided with a projecting head 4^a, which is adapted to project beyond the periphery of the cylinder 1, but not beyond the periphery of the collar 3, and when the parts are in the position shown in Figs. 1 and 2, this head 4^a engages the rear side of the ring 2, and the body of the key is engaged by a 40 screw 5 which is tapped therein through an opening 3^b in the collar 3, the parts being thus fastened together as shown in Fig. 2. The ends of the ring 2 may be shouldered as at 2^b, Fig. 3, to permit the body of the key 4 to pass between the ends of the sections of the ring and under the flange 2^a thereof (see Figs. 1 and 2).

The sections of the ring 2 are firmly held in place circumferentially of the cylinder by the overlying portion of the collar 3, and they are prevented from longitudinal movement on the cylinder by the groove 1^b in which they are placed. The collar 3 is kept from movement longitudinally of the cylinder by the key which is fastened to the collar by the bolt 5. The head 4^a of the key bearing against the outer side of the ring 2 prevents the collar moving inwardly, and the shoulder of the collar bearing against the inner surface of the ring 2 prevents the collar moving outwardly. The pressure exerted by the plate clamps on the plate tends to force the plate outwardly against the collar 3, and such pressure is transmitted through the collar 3 to the ring 2 and

through the latter to the outer wall of the slot 1^b with which the ring 2 is engaged.

When the parts are adjusted in the position shown in Figs. 1, 2 and 4, the collar 3 is in position to serve as proper abutment for a 7-column 13-ems plate cast from a dry matrix. If it should be desired to cast such plate from a wet matrix, the size of the plate would be slightly greater but the pressman could quickly prepare the plate cylinder therefor by simply first releasing and removing the key 4, then slipping the collar 3 inward until the sections of ring 2 are freed; then lifting out such sections and reversing them by turning them half around so that the flange 2^a will project toward the outer end of the cylinder and away from the collar 3^b, instead of toward the collar (as in Fig. 5), and replacing the ring in the groove; then replace the key 4 and secure it in position as before, and the cylinder will then properly accommodate and hold a 7-column 13-ems stereotype plate cast from a wet matrix. The notch 3^c in the collar allows the finger or a tool to be inserted in groove 1^c to start the key 4 outward when released.

In the drawing I have shown four parallel grooves 1^b and the ring 2 can be engaged with any one of these grooves according to the length of plate which it is desired to accommodate. Ring 2 may be positioned as shown in Figs. 2, 4 and 6; or reversed as shown in Figs. 5 and 7, according to whether the plates are cast from a dry or wet matrix.

The cylinder shown would be adapted to carry plates for 7 columns, 13-ems; or 8 columns 12-ems; or 8 columns 12½-ems; or 8 columns 13-ems; cast either from dry or wet matrices. By varying number of the slots 1^b and the positions of these slots, the cylinders can be primarily adapted for use with any desired number of different sizes of plates. The rings and collars can be adjusted in any groove as described, to secure the collar 3 in any desired position on the cylinder to accommodate the particular size of plate to be used.

The advantage of ready adjustment of the plate cylinders so that they can be readily used for eight or more different sizes of pages is obvious, and enables the publisher to install a press to operate on the smaller plates, cast from dry matrices and then to change to wet matrices; and also to enlarge the size of his plates and papers without any additional expense, such as is ordinarily involved if the press is capable of operating on one size plates only.

The means shown is so simple that a pressman can easily change the devices to suit any desired size of plate between editions, if he wishes. The advantage of being able to thus adapt the plate cylinder quickly and easily to suit plates cast from dry matrices

or wet matrices will be readily appreciated by pressmen.

With a tubular plate press, such as shown in my said patent, if one plate is properly positioned against the outer stop or collar 3, the center clamps (not shown) automatically take the proper positions, and the other plates put on the cylinder will be automatically properly located when the plate clamps 10 are tightened.

With this invention, the pressman or press erectors in the field can readily change the plate cylinders to suit any desired size of plate by shifting the collar 3, and the plates 15 will be properly centered on the cylinder.

By thus providing means to enable the cylinder to carry different sizes of plates, the plates can all be properly centered or located on the plate cylinder so as to insure 20 that the impression therefrom will be correctly positioned on the web and enable the folder to properly fold the papers without having to change the adjustment of the folders or the cutting cylinders.

25 What I claim is:

1. In combination, a plate cylinder, a plate stop device attached to said cylinder and reversible to suit plates cast from wet or dry matrices.

30 2. In combination, a plate cylinder, and adjustable plate stop member on said cylinder reversible to suit different sizes of plates.

35 3. In combination, a plate cylinder, a stop collar mounted on said cylinder, and a stop for said collar, said stop being reversible to hold the collar in position to suit plates cast from wet or dry matrices.

40 4. In combination, a plate cylinder, a collar adjustably mounted on said cylinder to suit different sizes of plates, and a stop for the collar, said stop being reversible to stop the collar in position to suit plates cast from wet or dry matrices.

45 5. In combination, a plate cylinder, a collar slidably mounted on said cylinder, and adjustable means for securing the collar to the cylinder; said means including a reversible member whereby the collar may be stopped in position to compensate for plates cast from wet or dry matrices.

50 6. In combination, a plate cylinder, a collar slidably mounted on said cylinder; adjustable means for securing the collar to the cylinder to suit different lengths of plates; said means including a reversible ring whereby the collar may be stopped in position to suit plates cast from wet or dry matrices.

60 7. In combination, a plate cylinder having a circumferentially disposed groove, a ring engaging the groove; and a stop on the cylinder adapted to engage the ring.

65 8. In combination, a plate cylinder having a circumferentially disposed groove, a

ring engaging the groove; and a stop collar slidable on the cylinder adapted to engage the ring.

9. In combination, a plate cylinder having an annular groove, a ring engaging the groove; and a stop slidable on the cylinder adapted to engage the ring.

10. In combination, a plate cylinder having an annular groove, a ring engaging the groove; and a stop slidable on the cylinder adapted to engage the ring; and means for locking the collar to the ring.

11. In combination, a plate cylinder having an annular groove, a sectional ring engaging the groove; and a collar slidable on the cylinder adapted to engage the ring.

12. In combination, a plate cylinder having an annular groove, a sectional ring engaging the groove; a collar slidable on the cylinder adapted to engage the ring; and means for locking the collar to the ring.

13. In combination, a plate cylinder having an annular groove, and a ring engaging the groove; said ring having a peripheral flange adapted to overlie the surface of the cylinder adjacent the groove.

14. In combination, a plate cylinder having an annular groove, a ring engaging the groove and having a peripheral flange adapted to project over the surface of the cylinder adjacent the groove, and a stop slidable on the cylinder adapted to engage the ring.

15. In combination, a plate cylinder having an annular groove, a ring engaging the groove; and a stop collar slidable on the cylinder and having a shoulder adapted to engage the ring.

16. In combination, a plate cylinder having an annular groove, a ring engaging the groove and having a peripheral flange projecting over the surface of the cylinder adjacent the groove, and a stop collar slid able on the cylinder having a shoulder adapted to receive the ring.

17. In combination, a plate cylinder having an annular groove, a ring engaging the groove; a stop collar slidable on the cylinder, said collar having a shoulder adapted to receive the ring; and means for locking the collar to the ring.

18. In combination, a plate cylinder having an annular groove, a sectional ring engaging the groove; and a collar slid able on the cylinder adapted to engage the ring; said ring having a peripheral flange adapted to overlie the surface of the cylinder adjacent the groove, and said collar having a shoulder adapted to receive the ring.

19. In combination, a plate cylinder having an annular groove, a sectional ring engaging the groove; a collar slid able on the cylinder adapted to engage the ring; and means for locking the collar to the ring; said ring having a peripheral flange adapted to project over the surface of the cyl-

inder adjacent the groove, and said collar having a shoulder adapted to receive the ring.

20. In combination, a plate cylinder having a plurality of annular grooves adjacent one end; a ring adapted to be engaged with a groove, and a stop on the cylinder adapted to engage the ring; whereby the cylinder may be adapted to carry plates of various sizes.

21. In combination, a plate cylinder having a plurality of annular grooves adjacent one end; a ring adapted to be removably fitted in any groove, and a stop collar slidably fitted on the cylinder adapted to engage the ring; whereby the cylinder may be adapted to carry plates of different sizes cast from wet or dry matrices.

22. In combination, a plate cylinder having a plurality of annular grooves adjacent one end; a sectional ring adapted to be removably fitted in a groove, and a stop collar slidably fitted on the cylinder adapted to engage the ring; whereby the cylinder may be adapted to carry plates of different sizes cast from wet or dry matrices.

23. In combination, a plate cylinder having an annular groove and a slot intersecting the groove, a ring engaging the groove; a stop slidable on the cylinder adapted to engage the ring; and a key fitted in said slot and means cooperating with the key to hold the collar and ring in engagement.

24. In combination, a plate cylinder having an annular groove; a sectional ring engaging any groove; a collar slidable on the cylinder adapted to engage the ring; said cylinder also having a slot intersecting the grooves; and means engaged with said slot to hold the collar and ring in engagement; whereby the cylinder may be adapted to carry plates of various size.

25. In combination, a plate cylinder having an annular groove, a ring engaging the groove having a flange adapted to project over the surface of the cylinder adjacent the groove, a stop slidable on the cylinder adapted to engage the ring; said cylinder also having a slot intersecting the grooves; and means engaged with said slot to hold the collar and ring in engagement; whereby the cylinder may be adapted to carry plates of various size.

26. In combination, a plate cylinder having a plurality of annular grooves adjacent one end; a ring adapted to engage with any groove; a stop on the cylinder adapted to engage the ring, whereby the cylinder may be adapted to carry plates of various size, cast from wet or dry matrices; said ring having a peripheral flange adapted to project over the surface of the cylinder adjacent the groove, and said collar having a shoulder adapted to receive the ring.

27. In combination, a plate cylinder for

printing presses having a plurality of annular grooves adjacent one end; a sectional ring adapted to be removably fitted in a groove; and a stop collar slidably fitted on the cylinder adapted to engage the ring; whereby the cylinder may be adapted to carry plates of different sizes cast from wet or dry matrices.

28. In combination, a plate cylinder having an annular groove, a sectional ring engaging the groove; a collar slidable on the cylinder adapted to engage the ring; said cylinder also having a slot intersecting the grooves and means engaged with said slot to hold the collar and ring in engagement; whereby the cylinder may be adapted to carry plates of different sizes cast from wet or dry matrices.

29. In combination, a plate cylinder having an annular groove, a ring engaging the groove; a stop slidable on the cylinder adapted to engage the ring; whereby the cylinder may be adapted to carry plates of various size, said ring having a peripheral flange adapted to project over the surface of the cylinder adjacent the groove; said cylinder also having a slot intersecting the groove; and a key fitted in said slot to hold the collar and ring in engagement.

30. In combination, a plate cylinder having an annular groove; a ring engaging the groove; a stop collar slidable on the cylinder adapted to engage the ring; whereby the cylinder may be adapted to carry plates of various size cast from wet or dry matrices; said ring having a peripheral flange adapted to project over the surface of the cylinder adjacent the groove; said cylinder also having a slot intersecting the groove; a key fitted in said slot, and means for fastening the key to the collar to hold the collar and ring in engagement.

31. In combination, a plate cylinder having an annular groove, a ring engaging the groove having a peripheral flange adapted to project over the surface of the cylinder adjacent the groove, said cylinder also having a slot intersecting the groove, a collar slidable on the cylinder adapted to engage the ring; and means engaged with said slot to hold the collar and ring in engagement, whereby the cylinder may be adapted to carry plates of various sizes; said collar having a shoulder adapted to receive the ring.

32. In combination, a plate cylinder having an annular groove, a sectional ring engaging the groove; a stop collar slidable on the cylinder adapted to engage the ring; said cylinder also having a slot intersecting the grooves, a key fitted in said slot to hold the collar and ring in engagement; and means for fastening the key to the collar; whereby the cylinder may be adapted to carry plates of different sizes cast from wet or dry matrices; said ring having a periph-

eral flange adapted to project over the surface of the cylinder adjacent the groove, and said collar having a shoulder adapted to receive the ring.

5 33. In combination, a plate cylinder, an annular plate stop detachably attached to said cylinder, and reversible to suit plates cast from wet or dry matrices, and means for securing the reversible stop in either position to the cylinder.

10

34. In combination, a plate cylinder, an annular plate stop adapted to be fixed at any one of a plurality of points on said cylinder, said stop being reversible to suit plates cast from wet or dry matrices, and means for securing the reversible stop in either position to the cylinder.

In testimony that I claim the foregoing as my own, I affix my signature.

HENRY F. BECHMAN.
